US00D864867S

(12) **United States Design Patent** (10) **Patent No.:** **US D864,867 S**
(45) **Date of Patent:** **** Oct. 29, 2019**

(54) **CORE FOR ELECTROMAGNETIC DEVICE**

(71) Applicant: **FANUC CORPORATION**, Yamanashi (JP)

(72) Inventors: **Masatomo Shirouzu**, Yamanashi (JP); **Takafumi Kajiya**, Yamanashi (JP); **Takuya Maeda**, Yamanashi (JP); **Kenichi Tsukada**, Yamanashi (JP)

(73) Assignee: **FANUC CORPORATION** (JP)

(**) Term: **15 Years**

(21) Appl. No.: **29/618,274**

(22) Filed: **Sep. 20, 2017**

(30) **Foreign Application Priority Data**

Mar. 23, 2017 (JP) 2017-005947

(57) **CLAIM**

The ornamental design for a core for an electromagnetic device, as shown and described.

DESCRIPTION

FIG. 1 is a perspective view of a core for electromagnetic device showing our new design;

FIG. 2 is a top plan view thereof; the bottom plan view is a mirror image of the top plan view

FIG. 3 is a front elevational view thereof;

FIG. 4 is a rear elevational view thereof; and,

FIG. 5 is a right side elevational view thereof; the left side elevational view is a mirror image of the right side elevational view.

1 Claim, 3 Drawing Sheets
